GIRDLE

Martin Goodman, New York, N. Y., assignor to
The Neatform Co. Inc., New York, N. Y., a corporation of New York

Application September 8, 1939, Serial No. 293,889

5 Claims. (Cl. 2--27)

This invention relates to girdles, and more particularly to elastic girdles.

The primary object of my invention is to generally improve elastic girdles for feminine wear. A more particular object is to provide a flexible girdle with an inelastic and preferably boned panel to help mold and confine the body, particularly at the stomach below the waist.

Further objects are to make such panel self-adjustable as to position, relative to the girdle, and to so mount the same on the girdle as not to interfere with the desired free elastic stretch of the girdle. Another object is to hold the panel in generally correct desired relation where it will do the most good, and to so arrange the locating or holding means as to keep the panel stretched out in taut condition when the girdle is being worn. Some of the connections from the panel to the girdle, preferably run to the lower edge of the girdle, and a further object is to prevent the lower edge of the girdle from being pulled up, for this would be uncomfortable to the wearer, and would destroy the desired smooth molded contours of the body. With this object in view, the girdle is provided with front and back garters for the support of stockings, and the connections from the inelastic panel are extended to the front and back garters.

In accordance with still another object and feature of my invention, the panel and its connections are made readily detachable from the girdle, thus facilitating laundering of the girdle, and also making it possible to use the girdle without the panel, when desired.

To the accomplishment of the foregoing, and such other objects as will hereinafter appear, my invention consists in the girdle and panel elements and their relation one to the other as hereinafter are more particularly described in the specification and sought to be defined in the claims. The specification is accompanied by a drawing, in which:

Fig. 1 shows a girdle embodying features of my invention, in position on the wearer;

Fig. 2 is a front elevation of the girdle turned inside out;

Fig. 3 is a similar view showing the rear of the girdle when turned inside out;

Fig. 4 is a horizontal section taken in the plane of the line 4--4 of Fig. 2;

Fig. 5 shows a modified form of the invention; and

Fig. 6 shows one of the hook-like connections used when the panel is made detachable.

Referring to the drawing, and more particu-

larly to Fig. 1, the complete foundation garment comprises an elastic girdle 12 and an inelastic panel 14, the latter preferably being provided with a number of bones or stays 16. The girdle is provided with front garters 18, and rear garters 20 which are not visible in Fig. 1, but which are clearly shown in Fig. 3. The panel 14 is preferably free of girdle 12 and is not stitched directly thereto. It is secured to the girdle at its upper corners, as is indicated at 26, while its bottom edge is drawn downwardly by elastic tapes 22 which preferably extend to the garters 18. The lower side portions of panel 14 are drawn rearwardly and downwardly by elastic tapes 24 and 26 which extend to the rear garters 20, as is clearly shown in Fig. 3.

Considering the arrangement in greater detail, the girdle 12 is preferably of conventional type, it being knit partially out of "Lastex" or similar elastic threads. The construction is such as to include horizontally or circumferentially extending laid-in elastic threads, so that the elasticity of the girdle is predominantly in a circumferential direction, although it is also yieldable in a vertical direction. The upper and lower edges are reinforced by appropriate elastic tapes 28 and 30 (Fig. 2), all in accordance with conventional practice.

The panel 14 is made of an inelastic or woven fabric having no elastic threads. The stays or bones 16 are secured in place by covering tapes 32 which are preferably located on the inside of the panel; that is, between the panel and the girdle, as is best shown in Fig. 4. It will be noted that the panel 14 is substantial in dimension, it extending downwardly for a distance of the order of two-thirds the height of the girdle. The ends of the elastic tapes 22, 24 and 26 are all stitched to the panel, preferably by disposing the same between the panel and an inside reinforcing tape 34 (Fig. 4). The tape 34 is stitched to the panel by two parallel lines of stitching 36, and these lines of stitching pass through the ends of the elastic tapes 22, 24, and 26, thus anchoring the same in position. Similar remark applies to the small loops of elastic tape 38 secured to the upper corners of the panel.

The ends of the elastic tapes are provided with special connections or hook-like members 40 which make them readily detachable. The nature of members 40 is clearly shown in Fig. 6, they comprising a closed loop 42 and an open loop or hook 44. Reverting now to Fig. 2 the lower ends of elastic tapes 22 are passed through the closed loops and are stitched in position at

46. Referring to Fig. 3, it will be seen that the tapes 24 and 26 preferably consist of one single length of reversely folded tape which passes through the closed loop of the hook 48. The comparatively short elastic tapes 38 at the top of the panel are preferably reversely folded loops of tape, the double ends of which are stitched to the panel.

The hooks of tapes 22 are received in small loops of elastic tape 59 (Fig. 2) which are stitched to the lower edge of the girdle at small pads or cushions 52. The reversely folded loops of elastic tape for the garters are also stitched to the girdle at the pads 52, and the attachment of the parts is strengthened by the presence of reinforcing tape 38 at the bottom of the girdle.

Referring now to Fig. 3, in a similar way the hooks of tapes 24 and 26 are received by elastic loops 54 which are stitched in position at pads 56, at which point the garter tapes are also attached. Common stitching may be used for securing all of the tapes and the pad together, so that the attachment is a secure one with the pull of the tapes 24, 26 being transmitted more or less directly to the garters.

The hooks of tapes 38 at the upper corners of the panel (Fig. 2) are received in loops of elastic tape 58 which are stitched to the girdle, preferably by a rectangle of stitching having lines of stitching which extend horizontally, as well as vertically, on loops 58.

The location of the loops 58 is such that the inelastic panel 14 is in loose or plaited or folded condition, as is clearly shown in Figs. 2 and 4, when the girdle is in unstretched condition. This insures that there will be no unnecessary restraint against stretching of the girdle when it is being worn, and at that time the panel is drawn sidewardly and downwardly to taut condition.

It is not essential to use hooks for detachable mounting of the panel. In Fig. 5, I show a modified form of girdle in which the elastic tapes holding the panel are permanently secured in position. In Fig. 5, the girdle is shown inside out, and the view is generally similar to Fig. 2, but the drawing is to a smaller scale and less detailed. Girdle 112 may be like the girdle 12 previously described. An inelastic panel 114 may be constricted like panel 14 previously described. It may be similarly provided with bones or stays which, however, are not shown in the drawing. Panel 114 is held downwardly by tapes 122 which are permanently connected to the lower edge of the girdle at the garters 118. The lower side portions of panel 114 are drawn sidewardly and downwardly by circumferentially extending elastic tapes 126 which extend rearwardly and downwardly to the rear garters, which are not visible in Fig. 5, but which correspond to the garters 20 in Figs. 2 and 3. The panel 114 is secured to the top of the girdle by triangular pieces 70 of heavy elastic tape or webbing. This is ordinary woven material with the elastic threads running diagonally; that is, parallel to the outside edges 72 of the triangular pieces. The upper edges 74 of the triangles are secured to the top edge of the girdle at the reinforcing tape 76, while the inside edges 78 of the triangular pieces are stitched to the side edges of panel 114. The stitching along the edges 78 does not go through the girdle 112. The top edge 80 of panel 114 is also preferably free of the girdle, and the parts are so proportioned that when the girdle is in unstretched condition the panel 114 is in loose

or plaited condition. The top edge 80 of panel 114 is preferably disposed at least a small distance below the top edge of the girdle. Thus the panel 114 is free of the girdle 112, except through the elastic connections 70, 122 and 126. The panel is therefore self-adjustable in position, and does not interfere with the desired stretch of the girdle 112.

However, the rearwardly extending tapes 126 function to spread or pull the sides of the panel apart into the desired taut condition in which the panel and its stays can be of the most benefit for correcting protrusion at the abdomen, and to give the body the desired smooth, molded contour, all without any of the discomfort attendant upon wearing heavy inelastic corsets.

It is believed that the construction, as well as the advantages of my improved girdle, will be apparent from the foregoing detailed description thereof. It will also be apparent that while I have shown and described my invention in several preferred forms, many changes and modifications may be made in the structures disclosed without departing from the spirit of the invention, as sought to be defined in the following claims.

I claim:

1. A foundation garment comprising an elastic girdle, a less elastic panel at the front of said girdle, the edges of said panel being free of the girdle for self-adjustment of position, said panel being in loose or plaited condition when the girdle is in unstretched condition, front and back garters at the bottom of the girdle, and elastic bands extending from the panel to the front garters, and additional elastic bands extending from the panel to the back garters.

2. A foundation garment comprising a knit circumferentially yieldable girdle, an inelastic panel at the front of said girdle, said panel extending downwardly from the upper edge of the girdle for a distance of about two-thirds the height of the girdle, bones or stays in said panel, the edges of said panel being free of the girdle for self-adjustment of position, said panel being in loose or plaited condition when the girdle is in unstretched condition, front and back garters at the bottom of the girdle, elastic bands extending downwardly from the bottom of the panel to the front garters, and additional elastic bands extending circumferentially rearwardly and downwardly from the lower side portions of the panel to the back garters.

3. A foundation garment comprising an elastic girdle, a less elastic panel at the front of said girdle, front and back garters at the bottom of the girdle, elastic bands extending downwardly from the bottom of the panel to the front garters, additional elastic bands extending circumferentially rearwardly and downwardly from the lower side portions of the panel to the rear garters, and hooks in said bands and at the upper corners of said panel for detachable mounting of the panel in the girdle.

4. A foundation garment comprising an elastic girdle, a less elastic panel at the front of said girdle, back garters at the bottom of the girdle, loops of elastic material extending upwardly at each of the garters, loops of elastic material secured near the upper edge of the girdle at each side of the panel, elastic bands extending circumferentially rearwardly and downwardly from the lower side portions of the panel and terminating in hooks detachably received in the loops at the rear garters, and additional hooks at the

upper corners of the panel detachably received in the loops at the top of the girdle, whereby the panel and elastic bands are readily removable from the girdle, the rearwardly extending bands being double bands having their front ends connected to the panel at vertically spaced points at the sides of the panel.

5. A foundation garment comprising an elastic girdle, a less elastic panel at the front of said girdle, bones or stays in said panel, triangular 10 pieces of elastic arranged with their apices down-

ward and having their inner edges secured to the panel and having their top edges secured to the girdle, front and back garters at the bottom of the girdle, elastic bands extending downwardly from the bottom of the panel to the front garters, and additional elastic bands extending circumferentially rearwardly and downwardly from the lower side portions of the panel to the rear garters.

MARTIN GOODMAN.
